UNITED STATES PATENT OFFICE.

JEFFREY JOHN WALLACE, OF AMITE, LOUISIANA, ASSIGNOR TO GULLETT GIN COMPANY, A CORPORATION OF LOUISIANA.

AUTOMATIC BALANCE FOR COTTON-PRESS SIDE DOORS.

Application filed September 8, 1927. Serial No. 218,238.

This invention relates to improvements in means for counterbalancing doors, particularly the type of doors common to cotton presses.

5 An object of this invention is primarily to provide a means for overcoming the objection of lifting the heavy side doors of a cotton press and eliminating the old and common method of having a weight attached and detached when operating the press doors.

10 A further object of this invention is to provide a counterbalance which will function to cooperate with a plurality of doors in the operation of a press, the weights or counterbalances being so arranged as to be independent of the doors, but at the same time be in an operative position constantly.

15 A further object of this invention is to provide a counterweight device having a combination of elements in no manner permanently attached or forming a part of the upper side doors of the press, a stop member suitably located on the side door being 20 the only contact this counterbalancing device has with the side door of the press.

25 Other objects of this invention will appear from the following detailed description of the device and as disclosed in the two sheets of drawings which are herewith made a part of this application.

In the drawings—

Figure 1 illustrates an elevational view of Figure 2 taken along line 1—1.

30 Figure 2 illustrates a side elevational view of a double box press used in the ginning of cotton, disclosing the counterbalance weights in operative relationship thereto.

35 Figure 3 represents an elevational view similar to Figure 1 except that the counterweights and operating elements are disclosed in position when one of the press doors is lowered.

40 Figure 4 illustrates a sectional view of the device disclosing the channel iron support and the method of pivotally arranging the door therein, together with the means of loosely mounting the counterbalance weights and links thereon.

45 Figure 5 illustrates a plan view of Figure 4.

Numerals 1 and 2 designate a double box press used for cotton ginning and made of any suitable material, having steel binding

elements and the like. The box members 1 and 2 are provided, according to this invention, with a counterbalance weight 3 adapted to function in connection with and in cooperation with both the doors 4 and 5 of the cotton press. The weight 3 may be made of any suitable material and of a shape desirable for the purpose, approximately as disclosed in Figures 1 and 3, wherein one end of each of the link elements 6 and 7 is pivotally attached to the weight 3 and the other ends being loosely mounted in one end of the levers 8 and 9. Fulcrum pins 10 and 11 are adapted to receive, pivotally mounted thereon, the lever elements 8 and 9 at approximately the center portions thereof. At a suitable position transversely of the doors 4 and 5 is adapted to be fastened stop members 12 and 13, which may be of angle iron structure or other suitable material and securely bolted or screwed to the doors, the free ends of the lever portions 8 and 9 being adapted to contact with the stop elements 12 and 13 in such a manner that when the door 4, for instance, is lowered into position disclosed in Figure 3, the free end of the lever 8 coming in contact with the stop portion 13 will force one end of the weight 3 upwardly as disclosed, the opposite end of the weight 3 being retained in approximately its original position. The fulcrum pins 10 and 11 in this invention are preferably formed and mounted as disclosed in Figures 4 and 5 wherein the pins are shown entirely independent of the press door and detached therefrom, being substantially supported in channel iron 14 which is securely fastened in some suitable manner near the lower edge of the door with portions extending beyond the sides of the box a sufficient distance to properly receive the fulcrum members 10 and 11.

50 The doors 4 and 5 are preferably, in this invention, pivotally hinged in the channel iron portions 14 entirely separated and irrespective of the fulcrum element 11, as at 15. The plan view of the fulcrum pin and hinged relationship, as disclosed in Figure 4, is shown in Figure 5 and clearly illustrates the means of holding the fulcrum pin in connection with the channel iron member 14 by means of bolt elements 16 and 17. In the above arrangement of elements, it is

to be noted that the parts form a combination in no manner permanently attached and forming no part of the upper side door of the press, stop elements 12 and 13 being the 5 only contacts this arrangement has with the side doors 4 and 5.

In operation and principle, this invention provides a means for overcoming the objection of lifting the heavy side doors of a cotton press and eliminating the old method of having a weight which ordinarily has to be attached and detached when operating the press. In this invention it is obvious that the weights are so arranged as to be independent of the doors, but in an operative position at all times. In connection with this invention, it may be stated, that all single and double box cotton presses used in gin houses are equipped with counterweights, 10 usually placed on a frame on top of the press. These counterweights are operated by means of a rope with a hook on the end, whereby, when the side doors of the press are to be let down, they are engaged with an 15 eye fastened to the side doors. This counterbalance is all right, perhaps, for certain purposes, but if the operator loosens the lock on the door, forgetting to engage the hook of the counterweight, the heavy door 20 will fall to the press platform with accompanying danger to the operator and much annoyance. To overcome this great disadvantage, the present invention has been devised, wherein a counterbalance, while not 25 30 in any manner attached to the side doors or the hinged pieces thereof, is always operative without attention on the part of the operator, by reason of a simple device of an angle iron bolted to the side doors of the 35 press in such a manner that on lowering or raising of the doors, the stop elements will come in contact with the lever operating 40 through a fulcrum bolted to the channel iron on the bottom end doors of the press and by 45 means of links will function to raise and lower the weight as clearly shown in the drawings.

Another advantage is that there is but one weight for the pair of side doors of each 50 press.

In the method for baling cotton, it may be stated that the lint cotton is usually fed into the press box on the left by means of an automatic tamper on the top thereof. The 55 long box is closed at the bottom by a follower which cannot fall out but is free to move upward. The tamper working up and down packs the cotton compactly in the box. The retainers are located near the top of the 60 box, thereby preventing it from springing back.

When a bale is tampered in the box, the containers are revolved around, the full box or container then being over a hydraulic ram 65 at the bottom and under the platen at the

top. The retainers are withdrawn and the ram is run up until the follower is at a pre-determined point. As the bagging, top and bottom, was in place at the start, the bale is ready to be tied out with steel bands. At 70 this point in the operation there is, of course, great outward pressure on the side doors of the press box, as cotton being of a spongy nature has a tendency when pressure is applied to spring outward. The side doors of 75 the press are very heavy to withstand this pressure and are held in place by suitable locks, the lever of which on one door is usually at the left, the link held fast to the door on the rear.

From the above general description of a cotton baling method, it may be easily seen why a counterbalance is needed. To lift the lever and allow the doors to fall is dangerous to the parts and to the workmen at the press. 80 So it will be perceived a counterbalance is quite necessary and is usually fastened to both front and rear doors by means of a hook on a rope and an eye on each door. Such a method has been for years in use. Operators claim that when the press man turns loose the door levers, forgetting the rope, 85 danger is imminent.

The counterbalance device, according to this invention, obviates the disadvantages 90 above described. The levers are not attached to the hinged piece at the side of the press door, but operate in relationship to the door and the weight by an up and down movement on a hinge pin fastened, not to the 95 side door, but to a channel iron on the end of the door.

It is to be understood that alterations and substitutions may be made in the above disclosure within the scope of the appended 100 claims without affecting the merits of this invention.

What I claim is:—

1. In a box press, a pair of doors hingedly attached to the box, a single counterbalance 110 weight for the pair of doors, levers for operating the weight, a fulcrum pin for pivotally mounting the levers, loosely mounted link members connecting the weight to one end of the levers, the opposite ends of 115 the levers being free, a stop member on each of the doors for contacting with the free ends of the levers thereby revolving the levers and raising the weight when a door is opened.

2. In a box press, a pair of doors hingedly attached to the box, a single counterbalance weight for the pair of doors, levers for operating the weight, a fulcrum pin for pivotally mounting the levers, loosely mounted link members connecting the weight to one end of the levers, the opposite ends of the levers being free, a stop member on each of the doors for contacting with the free ends of the levers thereby revolving the 120 125 130

levers and raising the weight when a door is opened, a support for the fulcrum pin independent of the door.

3. In a box press, a pair of doors hingedly attached to the box, a single counterbalance weight for the pair of doors, levers for operating the weight, a fulcrum pin for pivotally mounting the levers, loosely mounted link members connecting the weight to one end of the levers, the opposite ends of the levers being free, a stop member on each of the doors for contacting with the free ends of the levers thereby revolving the levers

and raising the weight when a door is opened, a support for the fulcrum pin independent of the door, consisting of a bracket attached to the box press. 15

4. In a box press, a plurality of doors for the box, a single counter balance weight for the doors, members for operating the weight, 20 a stop member on each of the doors for contacting with the members for operating the weight.

In testimony whereof I affix my signature.

JEFFREY JOHN WALLACE.
